UNITED STATES PATENT OFFICE.

JOHN B. HADAWAY, OF BROCKTON, MASSACHUSETTS.

SHOE-SEWING AND WELT-BEVELING MECHANISM.

SPECIFICATION forming part of Letters Patent No. 579,146, dated March 23, 1897.

Application filed August 5, 1896. Serial No. 601,772. (No model.)

To all whom it may concern:

Be it known that I, JOHN B. HADAWAY, a citizen of the United States, residing at Brockton, in the county of Plymouth and State of Massachusetts, have invented certain new and useful Improvements in Shoe-Sewing and Welt-Beveling Machines; and I do hereby declare the following to be a full, clear, and exact description of the invention, such as will enable others skilled in the art to which it appertains to make and use the same.

The present invention relates to shoe-sewing machines and more particularly to such machines having welt-beveling cutters arranged to bevel the welt of a shoe during the operation of sewing on the outer sole, such as disclosed in Letters Patent of the United States issued to me November 5, 1895, and numbered 549,125 and 549,124, respectively.

In the machines of the patents above referred to the welt-beveling attachments were carried by and dependent for their operation upon parts of the stitch-forming mechanism with which they were combined.

In the machine of Patent No. 549,124 the welt-beveling cutter is mounted upon and actuated by the slide carrying the awl as the same is retracted preparatory to puncturing the work for a new stitch, and upon the said retraction thereof the cutting of a portion of the welt is performed.

In the machine of Patent No. 549,125 the welt-beveling cutter is mounted upon the work-support, and upon a movement of the awl laterally while in the work to feed the same past the needle during the sewing operation it acts to force the work against the cutting edge of the knife, thus beveling a section of the welt substantially corresponding to or slightly greater than the length of the feed.

The constructions contained in the patents above referred to, while giving good results in operation and enabling the welt to be beveled during the stitching operation instead of beveling the same by hand or by a separate machine after the sewing had been completed, as was the practice prior to my inventions, are open to the objection that additional stress and strain are put upon the work-feeding mechanism by the necessity of carrying and

actuating the welt-beveling mechanism or feeding the work against the welt-beveling cutter, thus increasing the wear and tear upon the parts of such mechanism, rendering the machine liable to get out of order and to wear out more or less in a shorter time than before the welt-beveling mechanisms were added thereto.

The objects of the present invention are to remove the objections above noted and to generally improve the construction and operation of the machine and to produce a combined shoe-sewing and welt-beveling machine in which the work-feeding mechanism and welt-beveling mechanism shall be entirely independent of each other.

To this end the present invention consists of a combined shoe-sewing and welt-beveling machine in which the welt-beveling mechanism is distinct from and derives its movements entirely independently of the work-feeding mechanism; and it further consists of the devices and combination of devices which will be hereinafter pointed out and claimed.

I have illustrated my invention as embodying the stitch-forming and work-feeding mechanism substantially as shown in my patents above referred to, and such stitch-forming mechanism may be that of the Goodyear sole-stitching machine, which is the subject-matter of Letters Patent of the United States No. 473,870, issued to the Goodyear Shoe Machinery Company as the assignee of Zachary T. French and William C. Meyer, dated April 26, 1892, or any other suitable shoe-sewing machine with which my welt-beveling mechanism is adapted to be combined.

The present invention is illustrated in the accompanying drawings, in which similar letters refer to similar parts throughout the several views, and in which—

Figure 1 shows a plan of a portion of a shoe-sewing machine with the welt-beveling mechanism applied thereto. Fig. 2 is a side view thereof, looking toward the right in Fig. 1. Fig. 3 is a front elevation, parts being in section. Figs. 4, 5, and 6 are respectively a plan, a front elevation, and an end view of the carrier for the welt-beveling knife. Figs. 7, 8, and 9 are respectively a plan, a front

elevation, and an end view of the bracket and guide for the knife-carrier. Figs. 10, 11, 12, and 13 are respectively a top plan, an inverted plan, a front elevation, and a side elevation of the knife; and Figs. 14 and 15 are respectively a front elevation and an inverted plan of the presser-foot.

In the machine of the drawings, B³ is the feed-slide, having at one end the upright stand B⁴, which carries in its upper end a stud upon which is loosely mounted the awl-carrying segment a', to which is secured the awl a².

A³ is a portion of the fixed frame of the head of the machine, in which is set the fixed stud b, upon which is loosely mounted the needle-segment b', having secured thereto the curved and hooked needle b², and also there is mounted on said stud the needle-guard b⁴.

The presser-foot lever e' is mounted upon a pivot set in some fixed portion of the machine and operated as in the Goodyear machine hereinbefore referred to and has secured to its end the presser-foot e², as shown.

To the frame A³ is secured the work-support d, the upper surface of the forward end of which is cut away at d', as in the machine shown in Patent No. 549,124, before referred to, to accommodate the welt-beveling knife.

D represents a stand mounted upon and extending from frame A³, in which is formed a bearing D⁵ for the shuttle-driver D³.

A' represents a portion of the main shaft, and E a cam thereon, all of which parts, except as hereinafter noted, may be and conveniently are of the construction of similar parts in the said Goodyear machine.

C represents a suitable bracket which supports and guides the welt-beveling mechanism and which is secured to the stand D, adjacent to the bearing D⁵, by any suitable means, such as the screws c. The bracket C is provided with a suitable supporting and guiding device for the knife-carrier. In the machine of the drawings this supporting and guiding device consists of the parallel rods or bars c', secured to and projecting from the base of bracket C.

H represents a knife-carrier comprising the block h, having the smooth bearings h', adapted to fit and be reciprocated upon the guide rods or bars c', and which at its inner front end is provided with the bent arm h², to the end of which is secured the knife h and knife-guard h'. The end of arm h² is provided with the horizontally and vertically disposed ribs or bosses h³ h⁴, which take into corresponding recesses in the rear faces of the shanks of the knife and knife-guard h and h', which are secured thereto by the screws h⁵, the ribs and recesses insuring a correct positioning and secure fastening of the knife and knife-guard to the arm h². The arm h² extends outward and forward, as shown in Fig. 1, in such a position that the knife and knife-guard will be reciprocated back and forth within the cut-away portion d' of the work-support d.

For the purpose of reciprocating the knife-carrier H, I have provided the following mechanism: In an arm F of bracket C is formed a bearing f, in which is secured by a set-screw 70 m a short shaft f', upon which is pivoted the lever G. The lever G is provided with the bearings g', which are fitted to the ends of the shaft f', upon which it is free to oscillate.

The lower end of lever G is forked or recessed at p, as shown in dotted lines, Fig. 3, and embraces a block or roll q, mounted upon a stud r upon the back of block h of the knife-carrier H, and the upper end of said lever is inclined, as shown, and is provided with a 80 stud t, upon which is an antifriction-roll t', which rests against and is acted upon by the face of cam E. A spring n, secured at one end to a stud n' and at the other end to a stud n² upon the upper end of lever G, tends to hold 85 the roll t' in contact with the face of cam E.

The above-suggested arrangement is such that upon a revolution of shaft A' and cam E the face of said cam, acting upon the roll t', will impart an oscillating movement to lever G and through the connection of lever G with carrier H cause a reciprocation of said carrier and the knife h, mounted on the arm h thereof, thus causing said knife to bevel a section of the edge of the welt at each rotation of cam E as the sewing operation which unites the sole to the welt proceeds.

The operation of the stitch-forming and work-feeding mechanism of my machine is the same as that in the machines of the patent hereinbefore referred to and need not be specifically described herein, inasmuch as in my invention the welt-beveling mechanism is operated entirely independently thereof.

It will be noted that the bottom face of the 105 presser-foot e² is provided with a series of teeth or serrations e³ for the purpose of insuring a more positive holding of the edge of the sole and welt during the operation of the machine.

It will be noted that in the present invention the welt-beveling mechanism, being distinct from and deriving its movements entirely independently of the work-feeding mechanism, the parts of the work-feeding 115 mechanism are relieved from the extra stress and wear which resulted from mounting the welt-beveling cutters upon and actuating them by the work-feeding mechanism or from an arrangement in which the work-beveling 120 cutter is stationary and the work forced against the same by the feed to make the cut.

Having fully described my invention and its mode of operation, I claim as new and desire to protect by Letters Patent of the United 125 States—

1. In a shoe-sewing machine, the combination with the stitch-forming and work-feeding mechanism, of welt-beveling mechanism actuated independently of the work-feeding 130 mechanism, substantially as described.

2. The combination, with shoe-sewing

mechanism, of welt-beveling mechanism comprising a carrier, a knife-carrying arm projecting therefrom, a suitable support and guide for said carrier and means to actuate the same, substantially as described.

3. The combination, with shoe-sewing mechanism, of welt-beveling mechanism comprising a knife-carrier and suitable guiding devices upon which it is mounted and adapted to slide, of a cam-actuated spring-controlled lever for actuating said carrier, substantially as described.

4. The combination, with shoe-sewing mechanism, of welt-beveling mechanism comprising a knife-carrier, provided with an outwardly-bent arm extending from the lower edge thereof, substantially as described.

5. The combination with shoe-sewing mechanism, of welt-beveling mechanism, comprising a suitable bracket provided with supporting and guiding devices, a knife-carrier mounted upon and guided thereby, a lever pivoted to said bracket and actuating said

carrier, and means to actuate said lever, substantially as described.

6. The combination, with shoe-sewing mechanism, a presser-foot and means to actuate the same, of independently-actuated welt-beveling mechanism arranged to bevel a portion of the welt, while the work is clamped by the presser-foot, substantially as described.

7. The combination, with shoe-sewing mechanism, of welt-beveling mechanism comprising a bracket, an arm and guide-rods on said bracket, a knife-carrier adapted to be reciprocated on said guides, a lever pivoted to the arm, connections between the lever and knife-carrier, and means to oscillate the lever, substantially as described.

In testimony whereof I affix my signature in presence of two witnesses.

JOHN B. HADAWAY.
